ERNST R. RICHARDS, OF CHICAGO, ILLINOIS, ASSIGNOR TO SEARS, ROEBUCK AND CO.,
OF CHICAGO, ILLINOIS, A CORPORATION OF NEW YORK.

CORE-CHUCK.

1,037,988.

Specification of Letters Patent. Patented Sept. 10, 1912.

Application filed September 26, 1910. Serial No. 583,848.

To all whom it may concern:

Be it known that I, ERNST R. RICHARDS, a citizen of the United States, residing at Chicago, in the county of Cook and State of Illinois, have invented certain new and useful Improvements in Core-Chucks, of which the following is a specification.

This invention relates to a chuck adapted to lock a body to be rotated to a rotary 10 shaft or spindle.

The invention is especially adapted for locking a core upon which a roll of paper is wound to a suitable shaft or spindle so that the paper wound on the core may be unwound, or for the purpose of winding paper upon the core by rotation of said shaft.

One of the objects of this invention is to produce a chuck which may be roughly adjusted with relation to the object to be rotated, and which will automatically tighten 20 against said object upon rotation of one of said parts.

Another object of the invention is to produce a chuck of the character described 25 which is simple, strong, cheaply manufactured and very durable.

Other objects and advantages will become apparent as the invention is better understood from the following detailed description.

In the accompanying drawings, Figures 1 and 2 are, respectively, end and side elevations of one member of a chuck embodying the features of my invention. Figs. 3 and 4 are, respectively, side and end elevations of another member of the chuck. Fig. 5 is an elevation, partly in section, showing one manner of using my invention.

I have herein shown the invention as used 40 for locking a hollow core A to a rotary shaft B for the purpose of permitting a roll of paper C upon the core A to be unwound, or for the purpose of winding paper upon said core by rotation of the shaft B. It will be understood that, in either case, a suitable support, having bearings for the shaft B will be provided, and if a roll of paper is to be unwound, suitable tension means may be connected with the shaft so that the paper 45 will be unwound under the desired tension. I have deemed it unnecessary to illustrate the elements last mentioned, inasmuch as they are well known and may be of any desired or preferred construction.

55 A chuck embodying my invention is par-

ticularly well adapted, on account of its strength and durability, for use in connection with the large and heavy rolls of paper used by printing establishments.

Referring to Fig. 5, the chucks at opposite ends of the figure are identical in construction, with the exception that in one the spiral faces, to be later described, are right-hand, while in the other they are left-hand.

In the form herein shown by way of example, the chuck comprises a member 1 rotatably mounted upon, and slideable longitudinally of the shaft B, said member having a conical or tapered end 2 which is adapted to enter one end of the core A.

A suitable lug or key 3 upon the conical end 2 of the member is arranged to enter a notch a in the core A so that said core and member will rotate together. A member 4 fitting upon the shaft B has one or more screw-

threaded openings 5 therein, in which openings are threaded set screws 6 adapted to engage the shaft B for the purpose of positively locking the member 4 against movement with relation to said shaft. The ad-

jacent faces of the members 1 and 4 are spiral, said faces in the present instance representing one complete convolution of the spiral. It will be seen that when the core 80 A is rotated in one direction to unwind the

paper therefrom, the members 1 owing to the engagement of the key 3 in the notch a will rotate with the core. Assuming that the shaft B is under some tension as above explained, the section 4 of the chuck will not 90

rotate. As the section 1 rotates, the cam action of the contacting spiral faces on the sections will cause the section 1 to slide inwardly along the shaft B into engagement with the end of the core A. When the force

pressing the sections 1 inwardly equals the tension force holding the shaft B, the core A, the chucks and the shaft B will rotate as a unit. The spiral faces of the chuck sec-

tions are perpendicular to the axis of the 100 shaft B at all points, so that all force transmitted to the members 1 will be directly along the axis of said shaft. In a similar way, rotation of the shaft B in the proper direction to wind up paper on the core will

cause the spiral face on the member 4 to move the member 1 longitudinally of the shaft B, and into gripping engagement with the core A, the strength of the gripping action depending upon the amount of resi-

2
ance to rotation offered by the roll of paper C.

In the present instance I have shown two of the chucks, one at each end of the core; but it is obvious that one of these chucks may be displaced by a chuck of solid construction, the result being merely the difference in the amount of automatic adjustment which it will be possible to obtain.

10 It may also be seen that the core A may be of solid construction, the members 1 of the chucks being engaged with the core in any suitable way. In the case just mentioned, the shaft B would be displaced by spindles 15 upon the ends of which the chucks would be mounted.

All of the modifications above suggested, as well as others not specifically mentioned, fall within the spirit and scope of my invention. I therefore do not limit myself to the details herein shown and described.

I claim as my invention:

1. The combination of a rotary shaft; a member mounted on said shaft; a member 25 slidably and rotatably mounted upon said shaft; means independent of the slidable

member for securing the first mentioned member against rotation on the shaft, the adjacent faces of said members being of spiral formation; and clamping means on 30 said shaft opposite the sliding member.

2. The combination of a rotary shaft, a hollow core surrounding the shaft, and a chuck carried by said shaft at each end of the core, each of said chucks comprising a 35 section fixed to the shaft and a section rotatably and slidably mounted on the shaft, the latter section being cone shaped at one end and adapted to engage the end of the core, the adjacent faces of said sections extending radially across the adjacent ends of said sections and being of cam formation, whereby relative rotation of said sections will force the second mentioned section into engagement with the adjacent end of said 40 core.

In testimony whereof I affix my signature in presence of two witnesses.

ERNST R. RICHARDS.
